UNITED STATES PATENT OFFICE

FRANK PEREBENDA, OF HARRISON, NEW JERSEY

LOCK

Application filed March 25, 1929. Serial No. 349,564.

The invention relates to locks and the primary object of the invention is to provide a simple and novel lock structure having a plurality of bolts.

5 A further object of the invention is to provide a lock having a pair of sliding bolts, one being telescopic within the other and said bolts being adapted to be successively projected and retracted by a single key.

10 Another object of the invention is to provide a lock of the character stated having a relatively small number of parts capable of convenient and economical manufacture and assemblage; which is strong and durable and 15 not likely to get out of working order.

With the above general objects in view and others that will appear as the nature of the invention is better understood, the same consists of the novel construction, combination 20 and arrangement of parts hereinafter more fully described, illustrated in the accompanying drawings and pointed out in the appended claims.

In the drawings forming a part of this application and in which like designating characters refer to corresponding parts throughout the several views,

Fig. 1 is an elevation of the lock with the front plate removed and both bolts retracted;

30 Fig. 2 is a similar view showing one of the bolts projected;

Fig. 3 is a view similar to Figs. 1 and 2 with both bolts projected;

Fig. 4 is a sectional view taken on line 35 4-4 of Fig. 1;

Figs. 5 and 6 are perspective views of the bolts;

Fig. 7 is a perspective view of a tumbler;

Fig. 8 is a detail view of a guiding and 40 limiting member for the bolts;

Fig. 9 is a perspective view of one of the bolt springs with an attached guiding plate; and

Fig. 10 is a detail of a key used with the 45 lock.

Referring to the drawings in detail, the lock as shown, comprises a casing 11 having a removable front plate 12 formed with the usual key-hole and connected to the casing proper as by means of screws 13. The casing

has the usual edge plate 14 and bolt slot. A bolt 15 of substantially channel shape and cross-section having top and bottom flanges 16 and 17 receives for telescopic sliding movement therein a plain bolt 18. These bolts are 55 slidable beneath a pair of straps 19 and 20 near opposite ends of the casing and secured to the back thereof. The strap 20 is mounted on a raised portion or plate 21, being detachably secured in position at its angular bent 60 ends as by means of pins or screws 22. This strap is preferably stamped from a blank of sheet metal having an extension at one end formed into a right angular retaining plate 23 provided with an opening receiving a pivot pin 24. This pin carries a pair of springs 25 which are curved up and gaged at the upper end of the casing and the spring metal strips forming the same are coiled about the pivot 24 and having portions 26 extending 70 above bolts while their free ends are bent downwardly at right angles as indicated at 27. The bolt 15 is provided with a longitudinal slot 28 and the bolt 18 has a corresponding slot 29 which receives a substantially U- 75 shaped guiding and limiting member 30 with one leg longer than the other. The longer leg extends through an opening 31 in the strap 20 and into a corresponding opening in the plate 21 and this part serves to guide the 80 bolts in their movements as well as to limit such movements in opposite directions. Each part 26 is formed with a wing or plate portion 32 shown substantially triangular in shape and having a concaved recess 33 in its bottom. 85

At the top portion of the bolt 15 the flange 16 is cut away as indicated at 34 and provided with a pair of notches 35 and 36 at each end of this recess or cut away portion. The bottom flange 17 is also cut away as indicated at 37 for a considerable length intermediately of its ends and provided with relatively deep notch or recess 38. The bolt 18 has a pair of top notches 39 and 40 and one face is provided with a concaved recess 41 intermediate of its length adjacent the recess 37 and with a relatively wide and deep notch 42 in the thin wall of the bolt thus provided at the recess 41. The wings or plate portions 100

32 as is noted from the drawings, are gaged on opposite sides of the bolts and serve to retain them in a similar relation and guide them in their telescopic movements.

5 At the key-hole is provided a semi-circular bearing plate or tumbler support 43 which is secured to the back of the casing as indicated at 44 and comprises spaced portions between which a nib or wing 45 or a key 46 is designed to move in an arc. The key also has a nib or wing 47 with projections 48 and 49 extending in opposite directions and located at different radial distances from the axis. The plate 43 has a circular boss 50 around the circular part of the key-hole and receives thereon the circular portion 51 of a tumbler having a relatively thin slotted extension or wing 52 and another wing or arm 53 with a lug 54 projecting forwardly at right angles and of segmental shape as well as provided with a recess or groove 55 in its outer edge.

In the operation of the lock the key is inserted with the wing 47 disclosed in the slot of the wing 52. The wing 53 is thus in position to engage the notch 42 of the bolt 18 and the recess 55 receives the edge 33 of the adjacent wing 32. The bolts being retracted, the member 30 is near the front ends 30 of the slots 28 and 29 and the springs 25 force the bent ends or catches 27 into the front notches 25 and 40 of the bolts 15 and 18, respectively. By turning the key, the wing 53 engages the front end of the notch 42 and projects the bolt 18, the catch 27 being first disengaged from the notch 40 as the lug 54 engages the wing 42 and raises the portion or arm 26 against the action of its spring 25. During this operation the bolt 15 is stationary and the bolt 18 slides therein. Continued rotation of the key results in the wing 45 engaging the opposite plate 32 at its recessed edge 33 so as to disengage the other catch 37 from the notch 35 of the bolt 15 and then the wing 45 engages the notch 38 to project the bolt 15 while the wing 52 slides in a recess 41 and between the bolt 18 and the adjacent plate 32. At this time the projection 49 rides against the edge of the bottom bolt 18 and the projection 48 continues in engagement with the recess in the outer plate 32 so as to keep both catches 27 raised until they are released and snapped into the notches 36 and 39, thus holding the bolts locked in projected positions and against retraction or withdrawal except by the use of the proper key.

In retracting the bolts, the key is inserted and the reverse action takes place in the reverse order, the catches 27 being first disengaged from the notches 36 and 39 and the bolts retracted by engagement of the wings and respective notches 38 and 42 until the catches 27 snap into the notches 35 and 40. When the bolts are projected the slots 28

and 29 will be at their forward limit as shown on Fig. 3.

It will thus be seen that I have provided a very simple lock structure embodying a plurality, preferably two sliding bolts telescopic with relation to one another and also a lock which comprises relatively few parts which can be manufactured with facility and which are simple and not likely to get out of working order.

While there is described herein a preferred embodiment of the present invention, it is nevertheless to be understood that minor changes may be made therein without departing from the spirit and scope of the invention as claimed.

What I claim as new is:

1. A lock comprising a casing, a pair of sliding bolts guided in the casing, key operating means for successively projecting and retracting the bolts, spring catches adapted to engage the bolts in retracted and projected positions to hold them against movement, and a tumbler, said tumbler being operable by a key for disengaging the catches from the bolts prior to projecting and retracting said bolts.

2. A lock comprising a casing, a pair of sliding bolts in the casing, guides for the bolts, means for limiting the movements of the bolts in projected and retracted positions, one of said bolts having flanges slidably receiving the other bolt between, each bolt having a pair of notches in one edge, spring catches adapted to engage said notches in retracted or projected positions to hold the same against movement, plates on said catches, and a tumbler having a pair of wings, said tumbler being operable by a key provided with a pair of wings, one of the wings of the tumbler being slotted to receive the wings of the key, the opposite edge of the bolts having notches for engagement by the wings of the tumbler and key to successively disengage the catches from the first mentioned notches and to successively engage the other notch of the bolts to successively project and retract the bolts while the catches are disengaged.

3. A double bolt lock of the type described, comprising a casing, a pair of sliding bolts in the casing and telescoped one within the other, said bolts being adapted to successively project and retract, a plurality of spring catches, one engaging each bolt to hold the same against movement, and a tumbler, said tumbler being operable by a key for disengaging the catches from the bolts for successively retracting and projecting the bolts while the respective catches are disengaged.

4. A double bolt lock of the type described, comprising a casing, a plurality of sliding bolts in the casing and formed to telescope one within the other, said bolts being adapted to successively retract and project a plu-

rality of catches, one engaging each bolt to hold the same against movement, operating members carried by the catches, and a tumbler, said tumbler being operable by a key for disengaging the catches from the bolts prior to projecting and retracting the same.

5. A lock of the plural bolt type, comprising a casing, a plurality of bolts in the casing, guides for the bolts, said bolts being formed to telescope one within the other, each bolt having notches in one edge, spring catches engaging said notches in the bolts in projected and retracted positions to hold the same against movement, depending plates 10 on the catches, and a tumbler having wings, said tumbler being operable by a key provided with wings, one of the wings of the tumbler being slotted to receive the wings of the key, the opposite edge of the bolts having 15 notches for engagement by the wings of the tumbler and key to successively disengage the catches from the first mentioned notches and to successively engage the last mentioned notches of the bolts to successively 20 project and retract the bolts while the respective catches are disengaged.

In testimony whereof I affix my signature.
FRANK PEREBENDA.
